CLAIM

The ornamental design for an automobile wire wheel, as shown.

DESCRIPTION

FIG. 1 is a front elevational view of an automobile wire wheel showing my new design;

FIG. 2 is a rear elevational view thereof; and

FIG. 3 is a cross-sectional view thereof taken along the line 3—3 in FIG. 1, it being understood that the rear spokes have been omitted for clarity of illustration.

FIG. 1

FIG. 2

FIG. 3
